WALL-MOUNTED HIGH-VOLTAGE TAKE-OFF STRUCTURE

Ralph A. Withrow, Denver, Colo., assignor to Stearns-Roger Manufacturing Company, Denver, Colo., a corporation of Colorado

Tiled Oct. 5, 1959, Ser. No. 844,503
8 Claims. (Cl. 174—43)

This invention relates to power line supports and, more specifically, to an improved high-voltage take-off structure of a type particularly suited for use in conjunction with large transformer installations.

The conventional power take-off structures used in power plants, substations and the like for tapping onto the high-voltage transformers leave much to be desired in terms of static protection, cost, adequate support and uncluttered appearance. For example, most of these structures include a pair of latticed box columns fabricated from structural steel and located adjacent the main power plant transformer on heavy concrete footings and piers to which they are attached by suitable anchor bolts. The actual power take-off elements of the assembly are connected between these towers and the building at the elevation required to accommodate the high voltage leads entering the plant or substation. Also, in most instances, these towers are attached to the ends of the crane beam that support the crane rail of the plant gantry crane. At the top of these columns or towers, extension rods are customarily provided to which are attached the static arrestor lines, the purpose of which is to protect the main transformer lines from lightning or other static interferences.

Installations of this type have been found to be quite expensive to install from the standpoints of both labor costs and materials. The towers or columns must, of necessity, be located quite close to the main transformer and, when so positioned, they interfere with proper maintenance and repair of the unit. Also, for adequate protection of the main transformer against lightning and the like, it is of utmost importance that the static arrestor lines be located above the main power lines in a position displaced less than 45° from the vertical; yet, such a relation is often times quite difficult to achieve with ground-supported towers closely adjacent the transformer base. As a result, proper protection from static interferences is sometimes sacrificed or at least can be considered only marginal.

It is, therefore, the principal object of the present invention to provide a novel and improved power take-off structure for high-voltage transformer installations.

A second objective is the provision of an assembly of the class described which is considerably less expensive as it costs approximately one-third that of a conventional installation.

Another object of the invention is to provide a high-voltage take-off structure that leaves the transformer completely free of obstructions for purposes of maintenance and repair.

Still another objective is the provision of a wall-mounted take-off structure that is ideally suited for use in supporting static-arrestor lines in position to afford optimum lightning protection to the main power lines.

Additional objects of the claimed invention are to provide a high-voltage power take-off structure that is rugged, weather-resistant, simple to install, versatile, decorative in appearance and adaptable for use with most of the transformer installations found in power plants and substations.

Other objects will be in part apparent and in part pointed out specifically hereinafter in connection with the description of the drawings that follows, and in which:

2

FIGURE 1 is a side elevation, partly in section, showing the high-voltage power take-off assembly of the present invention attached in place on a building wall and connected to the main plant transformer;

5 FIGURE 2 is a section taken along line 2—2 of FIGURE 1, certain portions having been broken away to better show the construction; and,

FIGURE 3 is a front elevation with certain portions shown broken away to conserve space.

Referring now to the drawings, and in particular to FIGURE 1 thereof, it will be seen that the high-voltage power take-off structure of the present invention has been indicated in a general way by numeral 10 and is of a wall-mounted type being supported by a pair of horizontal steel girders 12 and 14 that comprise a part of the building wall 16 in a power plant, substation or other transformer installation. A pair of generally S-shaped uprights 18 formed of structural steel or aluminum have their inturned lower ends 20 welded or otherwise permanently attached to the lower of the horizontal building beams or girders 14 in transversely spaced substantially parallel relation to one another. The medial section 22 of the uprights, in the particular form shown, is substantially straight and angles upwardly and outwardly 25 relative to the building wall from its inturned lower end 20. Medial section 22 of the uprights is of a length substantially greater than the vertical spacing between the building girders 12 and 14. Thus, the brace or strut 24 that is used to attach the upright to the upper girder 12 30 is connected intermediate the ends of the medial section 22 as shown. Strut 24 is also welded or otherwise permanently attached to both the girder and upright in a manner to support the medial section of the latter in fixed spaced relation to the building wall. It should be mentioned that strut 24 in some power plant installations could be a projecting end of a longer beam passing through the building wall such as, for example, a crane beam of the type used to support the crane rail of a gantry crane or the like used inside the plant. In this 35 instance, girder 12 would probably not be used as support for the uprights.

The upper outturned end 26 of the uprights 18 is located some distance above the point of connection with strut 24 and it terminates in a connector 28 of a type 40 adapted to receive the insulated end 30 of static arrestor line 32. These static arrestor lines, of course, are usually considerably shorter and under much less tension than the main power lines 34 and, therefore, can be adequately supported at the free upper end of the uprights 18 rather than adjacent the brace 24. Also, by placing the static arrestor leads at the upper terminus of the uprights, they occupy a most favorable position to shield the main power lines as will be explained presently in connection with the detailed description of FIGURE 3.

55 Now, with reference to FIGURES 1 and 2, it will be noted that the uprights 18 are interconnected at a point intermediate the upper and lower ends thereof by a transversely extending beam-type subframe assembly that has been broadly identified by numeral 36 and which is preferably located closely adjacent braces 24 to provide for maximum structural strength. This subframe assembly 36, in the particular form shown, is of the latticed or truss-type designed to reduce the weight without sacrificing the necessary rigidity and other load-resistant characteristics. As illustrated, assembly 36 includes an aluminum or steel channel 38 fixedly attached to the front face of the uprights by bolts 40 and a pair of angle iron stiffeners 42 extending along the rear face of the uprights opposite the channel to which they are attached by a lattice work of cross braces 44. Of course, the particular construction of beam assembly 36 is of little significance apart from providing the required structural

strength dictated by sound engineering practice. Angle braces 46 have also been indicated as interconnecting struts 24 and girder 12 to prevent lateral shifting of the uprights and beam assembly. Hook-type connectors 48 are welded to the channel elements of the beam assembly at selected points thereon for use in attaching the insulator 50 and associated stub cable 52 that are secured to the main high voltage line 34 and provide means for connecting same to the supporting structure. A stub lead 54 is used to electrically interconnect the main line 34 with one of the contacts or posts 56 of the high-voltage transformer 58.

Finally, an examination of FIGURE 3 will reveal that the uprights 18 are spaced apart a distance substantially less than twice the height of the static arrestor lines 32 above the beam assembly 36. Another way of expressing the same relationship is that lines drawn from the point of connection of the static arrestor lines with the outturned ends 26 of the uprights that form an included angle of 45° with the latter will intersect one another as indicated at a point spaced above the beam assembly. These lines extending downwardly on both sides of the uprights at angles of 45° thereto define a tent-line zone beneath the static arrestor lines 32 wherein the main lines 34 are protected from lightning and other static electrical disturbances. Therefore, by connecting one of the main lines to a hook connector on the beam assembly located between the uprights and two additional main lines to connectors positioned adjacent the ends of the beam assembly outboard or beyond the adjacent upright a distance substantially less than the height of the static arrestor lines above said beam assembly, all three of the main lines will be adequately shielded within the protection zone.

Having thus described the several useful and novel features of the high-voltage power take-off structure of the present invention, it will become apparent that the many worthwhile objectives for which it was designed have been achieved. Although but a single specific embodiment of the invention has been illustrated and described in connection with the accompanying drawings, I fully realize that certain changes and modifications therein may well occur to those skilled in the art within the broad teaching hereof; hence, it is my intention that the scope of protection afforded hereby shall be limited only insofar as said limitations are expressly set forth in the appended claims.

What is claimed is:

1. A wall-mounted power take-off structure for use with high-voltage transformer installations and the like which comprises, at least two generally S-shaped uprights having an elongate medial section terminating at the lower end in an inturned portion and at the upper end in an outturned portion, the inturned portion being adapted for connection to a horizontally disposed reinforcing element of a building wall or the like with the medial section ranging upwardly therefrom, strut means

adapted to connect the medial section at a point intermediate the ends thereof to the building wall at a point spaced above the horizontal reinforcing element, first connector means carried by the outturned portion for attaching a static arrestor line to the upright, a transverse beam element interconnecting the uprights at a point intermediate the ends of the medial section maintaining same in fixed spaced substantially parallel relation to one another, and second connector means carried by the transverse beam element in position such that high-voltage lines attached thereto will be shielded from static discharges by the static arrestor lines located thereabove.

5. The power take-off structure as set forth in claim 1 in which the inturned portion of the upright bears an obtuse angular relation to the medial section thereof such that when said inturned portion is attached to a building wall in substantially normal relation thereto, said medial section will extend upwardly and outwardly therefrom.

10. The power take-off structure as set forth in claim 1 in which the transverse beam element is attached to the medial section of each upright at a point spaced beneath the outturned portion thereof a distance substantially greater than one-half the space between adjacent uprights.

15. The power take-off structure as set forth in claim 1 in which each of the second connector means is located on the transverse beam element within a 45° angular arc swung from the nearest upright about the first connector means carried thereby as a center.

20. The power take-off structure as set forth in claim 1 in which second connector means are located on both sides of each upright.

25. The power take-off structure as set forth in claim 1 in which the space between each of the second connector means and the point of intersection of the nearest upright with the transverse beam element is substantially less than the distance from said point of intersection to the first connector means carried by said upright.

30. The power take-off structure as set forth in claim 1 in which second connector means are located on both sides of each upright.

35. The power take-off structure as set forth in claim 1 in which the transverse beam element is attached to the uprights at a point closely adjacent the point of connection of the strut means therewith.

40. The power take-off structure as set forth in claim 1 in which second connector means are located on both sides of each upright.

45. The power take-off structure as set forth in claim 1 in which the transverse beam element is attached to the uprights at a point closely adjacent the point of connection of the strut means therewith.
